[57] **CLAIM**

The ornamental design for a hand and wrist support for athletic use, substantially as shown and described.

DESCRIPTION

FIG. 1 is a side perspective view of a hand and wrist support for athletic use showing my new design;

FIG. 2 is a top front perspective view thereof;

FIG. 3 is a rear perspective view thereof;

FIG. 4 is a perspective view as seen from the side opposite FIG. 1; and

FIG. 5 is a cross-section taken on line 5—5 of FIG. 3. The broken lines representing the human hand are shown for illustrative purposes only.
